UNITED STATES PATENT OFFICE.

EVERETT P. LARSH, OF DAYTON, OHIO, ASSIGNOR TO THE BURNETT-LARSH MANUFACTURING COMPANY, OF DAYTON, OHIO, A CORPORATION OF OHIO.

DESIGN FOR A PUMP-CASING.

53,336.

Specification for Design.

Patented May 20, 1919.

Application filed February 12, 1916. Serial No. 78,065. Term of patent 14 years.

To all whom it may concern:

Be it known that I, EVERETT P. LARSH, a citizen of the United States, residing at Dayton, in the county of Montgomery and State of Ohio, have invented a new, original, and ornamental Design for a Pump-Casing, of which the following is a specification, reference being had to the accompanying drawing, forming part hereof.

The figure is a side elevation of a pump casing, showing my new design.

I claim:

The ornamental design for a pump casing, as shown.

In testimony whereof, I have hereunto set my hand this 9 day of February A. D. 1916.

EVERETT P. LARSH.

Witnesses:

C. E. BURNETT,
M. C. ROYER.
